UNITED STATES PATENT OFFICE.

HOMER S. WITHAM, OF JACKSONVILLE, FLORIDA.

TRUNK-STRAP AND FASTENER THEREFOR.

1,376,240.

Specification of Letters Patent. Patented Apr. 26, 1921.

Application filed October 20, 1920. Serial No. 418,307.

To all whom it may concern:

Be it known that I, HOMER S. WITHAM, a citizen of the United States, residing at Jacksonville, in the county of Duval and 5 State of Florida, have invented certain new and useful Improvements in Trunk-Straps and Fasteners Therefor, of which the following is a specification.

This invention relates to trunk straps and 10 fasteners therefor of the type used for tightening and fastening the strap after the trunk is closed.

The object of the invention is to provide 15 simple and efficient trunk fastening means of this character which are designed as substitutes for leather trunk straps being connected so as to securely retain the trunk in closed position, all of the parts being composed of metal whereby the life thereof is 20 greatly prolonged.

Another object is to provide fasteners for 25 the straps which are connected to take up the concentrated pressure of the straps and cause them to slide properly during the tightening thereof.

With these and other objects in view, the 30 invention consists in certain novel features of construction as hereinafter shown and described, and then specifically pointed out in the claims, and in the drawings illustrative of the preferred embodiment of the invention.

In the accompanying drawing:

Figure 1 represents a perspective view of 35 the portion of a trunk body and its top with the improved fastener and strap constituting this invention shown applied, the fastener being open, and

Fig. 2 is a similar view with the fastener 40 shown closed.

In the embodiment illustrated the trunk body B and its top T have mounted thereon metal panels or plates 1 and 10, respectively, said plates being so positioned as to aline 45 transversely of the trunk when applied and the top is in closed position.

The plate 1 which is secured to the body B by any suitable means is provided at its upper end with an aperture 2 for a purpose presently to be described. Projecting 50 from the outer face of plate 1 are two longitudinally extending laterally spaced parallel ribs 3 and 4 preferably made integral with plate 1 and which carry on their inner faces catch members 6. These catch mem-

bers 6 are in the form of resilient metal strips secured at one end to the ribs 3 and 4 while at their free ends they are provided with outwardly and laterally projecting studs 5 for a purpose presently to be described. Projecting laterally outward from the catch members 6 midway the ends thereof are two push buttons 7 which slide freely in apertures formed in the ribs 3 and 4 and are adapted by compression to retract the 65 studs 5 for a purpose presently to be described.

The trunk straps are each composed of two laterally spaced high grade crucible steel wires 8 which are connected at one end with the lower end of plate 1 and extend around the body of the trunk up over the top thereof and connected with a slide 11 presently to be described.

Mounted on the trunk and top at intervals are aligned guides 9 for the wires 8, said guides being shown in the form of metal castings having longitudinal grooves in their faces in which the wires 8 are guided to permit them to slide freely when tightened and to prevent lateral movement thereof.

The plate 10 which is carried by the top T has undercut longitudinally extending side flanges 10^a in which the slide 11 is 85 mounted to reciprocate for tightening or loosening the wires 8 constituting the trunk strap. The slide 11 has a plurality of rearwardly inclined rack teeth 12 with which are designed to be adjustably engaged a substantially rectangular wire loop 18 which connects said slide with a lever 15.

Longitudinally disposed guards 13 and 14 are arranged over the rack teeth 12 and are designed to retain the loop-shaped wire 95 18 connected with the slide 11, the end cross bar of said loop being of a length substantially equal to the length of the teeth and the side bars thereof fitting outside the guards 13 and 14.

The lever 15 is shown in the form of a substantially rectangular metal plate having outturned side flanges 16 through which the fulcrum 15^a of the lever passes at one end and is mounted in apertured ears 10^b 105 carried by plate 10 near its lower end. The flanges 16 have apertures 17 at their outer ends, the aperture in one flange registering with that in the other and which are designed to receive the studs 5 carried by the 110

latch members 6 when the fastener is in closed operative position.

A latch member 19 in the form of a metal bar or plate is pivoted at one end between 5 apertured ears 10^a arranged in advance of the ears 10^b in planes inside that occupied by said ears as is shown clearly in Fig. 1. The plate 19 has a tongue 20 on its inner face, the inner edge of which is undercut as 10 shown at 20^a forming a hook-like member which is designed to enter the aperture 2 in plate 1 when the fastener is closed and assist in retaining the trunk in closed position. This plate 19 has its outer end outturned 15 to form a finger grip 21 to facilitate the opening of the latch.

In the use of this combined trunk strap and fastener, the trunk top having been closed as shown in Fig. 1 the latch member 20 19 is shut being moved downwardly until the tongue 20 thereof enters and has a hook-like engagement with the walls of the aperture 2. After the latch 19 has been closed the loop-shaped wire 18 has its free end 25 engaged with one of the teeth 12 of slide 11 and then the lever 15 with which said loop is connected is moved downwardly thereby forcibly moving slide 11 down with it and exerting a tightening action on the 30 wires 8. When the lever 15 is moved to its extreme downward limit over the latch 19, the catch members 6 on plate 1 the studs 5 of said members will engage with the apertures 17 in the lever as shown in Fig. 2 and 35 owing to the resiliency of the strips 6 will operate to hold the lever in closed position. When it is desired to release the fastener the push buttons 7 are moved inwardly simultaneously a sufficient distance to retract 40 the studs 5 and disengage them from the apertures 17 in lever 15. The tension of the wires 8 will then assist in the opening of said lever 15 until it reaches the position shown in Fig. 1. After lever 15 has been 45 opened the latch 19 is raised thus releasing the trunk top T and permitting it to be opened in the usual manner.

While one strap only has been described above, it is to be understood that two or 50 more may be used according to the size of the trunk, two being usually employed.

A trunk strap and fastener constructed as above described being composed entirely of metal will obviously outlast a number of 55 leather straps such as are ordinarily used on trunks and the high grade steel wires 8 will resist great strain.

The preferred embodiment of the invention is disclosed in the drawings and set 60 forth in the specification, but it will be understood that any modifications within the scope of the claims may be made in the construction without departing from the principle of the invention or sacrificing any 65 of its advantages.

What is claimed is:

1. The combination with a trunk strap; of a plate secured to one end thereof and adapted to be attached to a trunk body, another plate to be attached to a trunk top 70 to aline with the body carried plate, a slide mounted on one of said plates, a lever fulcrumed on said slide carrying plate and connected with the slide, and coöperating means carried by said lever and the other 75 plate to tighten the strap and lock the plates connected.

2. The combination with a trunk strap; of a plate secured to one end thereof and adapted to be attached to a trunk body, another plate to be attached to a trunk top 80 to aline with the first mentioned plate, a slide mounted on one of said plates, a lever fulcrumed on said slide carrying plate and adjustably connected with said slide, and coöperating means carried by said lever and the other plate for tightening the strap 85 and locking the plates connected.

3. The combination with a trunk strap; of a plate secured to one end and adapted 90 to be attached to a trunk body, another plate to be attached to a trunk top to aline with the first mentioned plate, a slide mounted on one of said plates, a lever fulcrumed on said plate, a rod adjustably connecting said lever with said slide, a guard 95 to hold said rod engaged with the slide, and coöperating means carried by said lever and the other plate for locking the plates connected and holding the strap in tightened 100 position.

4. The combination with a trunk strap composed of a high grade steel wire; of a plate secured to one end of said wire and adapted to be secured to a trunk body, another plate to be attached to the trunk top, 105 a slide carried by said last mentioned plate and having a plurality of longitudinally spaced teeth on its outer face, a lever fulcrumed at one end on said plate, a rod connected with said lever intermediate its ends and adjustably engaged with the teeth of 110 said slide, and coöperating means carried by said lever and the other plate for locking the lever engaged with the plate. 115

5. The combination with a trunk strap composed of a high grade steel wire; of a plate secured to one end of said wire and adapted to be secured to a trunk body, another plate to be attached to the trunk top, 120 a slide carried by said last mentioned plate and having a plurality of longitudinally spaced teeth on its outer face, a lever fulcrumed at one end on said plate, a rod connected with said lever intermediate its ends and adjustably engaged with the teeth of 125 said slide, and coöperating means carried by said lever and the other plate for locking the lever engaged with the plate, said means comprising a spring pressed clutch 130

member carried by said plate, the lever having an aperture for engagement by said catch member.

6. A fastener for trunks and the like comprising two plates adapted to be secured to the members to be fastened, one of said plates having a laterally projecting apertured rib, a resilient metal strip secured at one end to one face of said rib and having a laterally extending stud passing through the aperture in said rib, the other plate having a lever fulcrumed thereon and provided with an aperture to receive said stud when the lever is in closed position, and means for depressing said strip to release the stud from the lever.

7. A fastener for trunks and the like comprising two plates to be secured to the members to be connected, one of said plates having a laterally projecting rib provided with a plurality of longitudinally spaced apertures, a resilient metal strip secured at one end to one face of said rib and having a stud and a push button passing through the apertures in the rib, the other plate having a lever fulcrumed at one end thereto, and provided with an apertured flange for engagement with said stud, the push button being depressible to disengage the stud from the lever.

8. The combination with a receptacle having a hinged top, a plate secured to the body of said receptacle, another plate secured to the top thereof in position to line with the first mentioned plate when the top is closed,

a pair of laterally spaced high grade steel wires secured to the first mentioned plate and adapted to pass around the body and top of the receptacle, grooved castings carried by said body and top to form guides 40 for said wires, a slide connected with the free ends of said wires and mounted to reciprocate on the top carried plate, and a lever connected with said slide, said lever and the first mentioned plate having co- 45 operating locking means to hold the lever in closed position.

9. A fastener for trunks and the like comprising two plates to be secured to the members to be connected and arranged in 50 position to aline with each other, one of said plates having an aperture therein, and a pivoted latch carried by the other plate and provided with a hook-shaped tongue to engage said aperture to lock the plates connected.

10. A fastener for trunks and the like comprising two plates to be secured to the members to be connected and arranged in 55 position to aline with each other, one of said plates having an aperture therein, and a pivoted latch carried by the other plate, said latch having a lateral extension on its lower face with the inner edge undercut to form a hook-like member to enter and interlockingly engage with the aperture in the other plate.

In testimony whereof, I affix my signature hereto.

HOMER S. WITHAM.
